UNITED STATES PATENT OFFICE

HENRY VINCENT JAMES, OF CINTRA, ENGLAND

PAPER WEB TENSIONING MEANS FOR REEL-FED PRINTING PRESSES

Application filed August 25, 1930, Serial No. 477,772, and in Great Britain May 29, 1930.

This invention relates to paper reel and web feed control apparatus for rotary printing presses wherein the web is fed to the press continuously from successive reels which are supplied by a magazine reel feed system, anchored belts or bands being applied directly to the periphery of the reel in use for direct reel control and web tensioning purposes.

10 It is the usual practice to use a number of the said belts, generally four, tied between flexible floor anchorages at their one ends and a rotatable roller at their other ends located in such a position that the belts will be within the arc of the reel throughout its 15 unwinding life, tension being obtained by rotation of the roller actuated by solenoid or torque motor, or by weights suspended directly by the belts, for the purposes of web 20 feed tension and to prevent reel overrun at slow down or stoppage of the press.

My invention consists in improved means 25 for rotating the belt tensioning roller for the purposes described and primarily consists in an epicyclic or three-element gear having one element which I will refer to as the first, mechanically attached to and adapted to rotate the belt tensioning roller, another element, which I will call the second, driven by 30 an electric motor, and the remaining or third element suitably electro-magnetically or electro-dynamically braked for the purpose of varying the effort applied to the first element, means being provided for regulating the 35 brake torque of the third element.

In one method of carrying out my invention I employ two electro-dynamic machines of like characteristics and energize them from a suitable electricity supply service, the two 40 machines thereby normally rotating at like speeds but in relatively opposite directions without causing any movement of the first element but by weakening the field of one of the electro-dynamic machines which I now 45 refer to as the electric motor coupled to the second element, rotary movement or tendency to movement is imparted to the first element corresponding in foot pounds or torque pounds to the increased speed of the electric 50 motor and that of the second electro-

dynamic machine which can be referred to now as the generator coupled to the third element, and the value of the energy regenerated by the latter back into the line.

By this means actual movement or tendency to movement in torque applied to the first element and the web tensioning roller to which it is geared is established corresponding to the increased speed of the electric motor and the output of the generator, 55 whether the first element actually be rotated for the purpose of the required tension on the belts or held under torque-tension for the purposes described.

A wide range of tension variation for web 60 and reel control with great flexibility and sensitiveness of operation is obtained by the use of the apparatus described and a variable resistance of ordinary type in the field of the electric motor, the system at the same 65 time being regenerative and economical.

Slack belts without tension are obtained either by deenergizing the two electro-dynamic machines or by re-establishing full 70 equal effective voltage across the armatures and fields of both machines, under which condition they will run at like speeds but in reverse directions of rotation, no torque then being imparted to the first element. Where 75 the former method is adopted and tension released by the de-energizing of the electro-dynamic machines a like tension will be re-established when same are re-energized providing the effective field value of the electric 80 motor has not meanwhile been altered.

Two of the ways in which the invention can be carried out are illustrated by way of example in the accompanying drawings in 85 which

Fig. 1 is a side elevation of two electro-dynamic machines of like characteristic each coupled to one of two of the elements of a three-element gear;

Fig. 2 is an end view of such a gear and one of the electro-dynamic machines connected with a belt tensioning roller, the belt being shown in contact with a reel;

Fig. 3 is a vertical section of a suitable three-element or epicyclic gear;

Fig. 4 is a circuit diagram showing how 100

the electro-dynamic machines are energized in parallel and how one of them is directly controlled with regard to speed;

Fig. 5 is a side elevation of an alternative arrangement in which one of the electro-dynamic machines of Fig. 1 is replaced by an electromagnetically controlled friction brake; and

Fig. 6 is an end view of such a brake with part of its associated control apparatus shown in diagram form.

In the example according to Figs. 1 to 4 the first element of the three-element or epicyclic gear comprises a sprocket wheel 1 rigid with a carrier 2 for two planet wheels 3—3 meshing with the sun wheels 4 and 5 of the second and third elements respectively of the gear. The two latter elements include shafts 6 and 7 on the inner ends of which the wheels 4 and 5 are mounted and the outer ends of which are connected one with an electro-dynamic machine 8 and the other with an electro-dynamic machine 9 of like characteristic and oppositely rotatable with respect to machine 8.

When the machines 8 and 9 are equally energized their sun wheels 4 and 5 rotate the planet wheels idly, the carrier 2 and the sprocket remaining stationary. Upon speeding up the machine 8 by means of a variable resistance 10 in series with the field of 8 the wheels 3—3 climb over the wheel 5 and thus the carrier 2 and sprocket 1 are turned on shafts 6 and 7 and through a chain drive 11—12 turn a belt roller 13 which tensions the belts such as 14 against the pull of springs 15 anchoring the bottoms of the belts so that the reel 16, indicated in chain line, is retarded, due to the contact between its periphery and the belts, and the running web is tensioned, to extents determined by the difference in torque pounds between the machines 8 and 9. The machine 8 is slowed down by cutting out the resistance in its field circuit, and thereby brought to normal speed, the speed of the electro-dynamic machine 9 will likewise be reduced to normal at which point it will develop a counter E. M. F. equal to that of the line only, and thereupon run at the same speed as electro-dynamic machine 8, when all turning effort and tendency on the part of element 1 will cease and all parts come to and remain in normal condition.

In place of one of the machines 8 or 9 and the resistance 10 I may use an electromagnetically controlled friction brake such as is shown in Figs. 5 and 6. Normally the machine 8 rotates a brake drum 17 through the three-element gear which is identical with that shown in Fig. 4, the said drum rotating oppositely with respect to the machine 8 and the carrier 2 of the gear remaining stationary. When it is desired to tension the reel and web controlling belts (such as 14, Fig. 1) a solenoid 18 is energized and

retracts its core 19 which tilts an arm 20 and thereby presses spring-released friction shoes 21 into engagement with the inner periphery of the drum 17, so that the drum is retarded and retards the third element of the gear, whereupon the carrier 2 turns and turns the belt roller (such as 13, Fig. 2). In order that the retarding effort may be varied a variable resistance 22 is arranged in series with the solenoid, the more the core is retracted the greater the retardation of the brake with correspondingly increased turning effort or turning tendency of the carrier 2.

What I claim as my invention is:

1. In apparatus for the control of a rotary paper reel and the paper web therefrom which supplies a printing machine, a friction band which acts on the reel for restraining the rotation of the reel and tensioning the web, a tensioning roller for the band, and means for rotating the roller for tensioning the band to vary the effort of the band on the reel, said means comprising an epicyclic gear having three rotary elements, a coupling between one of said elements and the roller, an electro-dynamic machine, a coupling between said machine and another of the gear elements, and variable retarding means coupled to the remaining gear element.

2. In apparatus for the control of a rotary paper reel and the paper web therefrom which supplies a printing machine, a friction band which acts on the reel for restraining the rotation of the reel and tensioning the web, a tensioning roller for the band, means for rotating the roller for tensioning the band to vary the effort of the band on the reel, said means comprising an epicyclic gear having three rotary elements, a coupling between one of said elements and the roller, two electro-dynamic machines, a coupling between one of said electro-dynamic machines and another of the gear elements, a coupling between the other of said electro-dynamic machines and the remaining gear element, and control means for altering the speed of one of the electro-dynamic machines with respect to the speed of the other of such machines.

3. In apparatus for the control of a rotary paper reel and the paper web therefrom which supplies a printing machine, a friction band which acts on the reel for restraining the rotation of the reel and tensioning the web, a tensioning roller for the band, means for rotating the roller for tensioning the band to vary the effort of the band on the reel, said means comprising an epicyclic gear having three rotary elements, a coupling between one of said elements and the roller, an electro-dynamic machine, a coupling between said machine and another of the gear elements, a friction brake coupled

to the remaining element of the gear, and means for regulating the retarding effort of said brake.

4. In apparatus for the control of a rotary paper reel and the paper web therefrom which supplies a printing machine, a friction band which acts on the reel for restraining the rotation of the reel and tensioning the web, a tensioning roller for the band, means for rotating the roller for tensioning the band to vary the effort of the band on the reel, said means comprising an epicyclic gear having three rotary elements, a coupling between one of said elements and

10 the roller, two electro-dynamic machines of like characteristic, a coupling between one electro-dynamic machine and another element of the gear, a coupling between the other electro-dynamic machine and the remaining element of the gear, and a variable resistance for altering the relative speeds of the two said electro-dynamic machines.

5. In apparatus for the control of a rotary paper reel and the paper web therefrom which supplies a printing machine, a friction band which acts on the reel for restraining the rotation of the reel and tensioning the web, a tensioning roller for the band, means for rotating the roller for tensioning the band to vary the effort of the band on the reel, said means comprising an epicyclic gear having three rotary elements, a coupling between one of the said elements and the roller, an electro-dynamic machine, a coupling between said machine and another of the gear elements, an electro-magnetic friction brake coupled to the remaining element of the gear, and a variable resistance for regulating the retarding effort of the said electro-magnetic friction brake.

6. In apparatus for the control of a rotary paper reel and the paper web therefrom which supplies a printing machine, a friction band making contact with the periphery of the reel for restraining the rotation of the reel and tensioning the said web, a roller to which one end of the band is attached, an anchorage at the other end of the band and means for rotating the roller for tautening and slackening the belt and so varying the effort of the band on the reel, the means for rotating the roller comprising an epicyclic gear, a coupling between one element of the gear and the roller, an electro-dynamic machine, a coupling between this electro-dynamic machine and another element of the gear, and means coupled to a further element of the gear for retarding the said further element and causing the electro-dynamic machine to impart a rotary turning effort to the element coupled to the roller and impart a like effort to the said roller.

7. In apparatus for the control of a rotary paper reel and the paper web therefrom

which supplies a printing machine, a friction band making contact with the periphery of the reel for restraining the rotation of the reel and tensioning the web therefrom, a roller to which one end of the band is attached, an anchorage at the other end of the band and means for rotating the roller for tautening and slackening the belt and so varying the effort of the band on the reel, the means for rotating the roller comprising an epicyclic gear, a coupling between one element of the gear and the roller, two electro-dynamic machines, a coupling between another of the elements of the gear and one of the electro-dynamic machines and another coupling between a third element of the gear and the remaining machine, and control means for altering the speed of one of the electro-dynamic machines with respect to that of the other machine for the purpose of transmitting, through the gear, a rotary turning effort to the element coupled to the roller.

8. In apparatus for the control of a rotary paper reel and the paper web therefrom which supplies a printing machine, a friction band making contact with the periphery of the reel for restraining the rotation of the reel and tensioning the said web, a roller to which one end of the band is attached, an anchorage at the other end of the band, and means for rotating the roller for tautening and slackening the belt and so varying the effort of the band on the reel, the means for rotating the roller comprising an epicyclic gear, a coupling between one element of the gear and the roller, an electro-dynamic machine, a coupling between this electro-dynamic machine and another element of the gear, a friction brake coupled to a further element of the gear, and means for regulating the retarding effort of the said brake to cause the electro-dynamic machine to impart, through the gear, a rotary turning effort to the element coupled to the roller and to impart a like effort to the said roller.

9. In apparatus for the control of a rotary paper reel and the paper web therefrom which supplies a printing machine, a friction band making contact with the periphery of the reel for restraining the rotation of the reel and tensioning the web therefrom, a roller to which one end of the band is attached, an anchorage at the other end of the band and means for rotating the roller for tautening and slackening the belt and so varying the effort of the band on the reel, the means for rotating the roller comprising an epicyclic gear, a coupling between one element of the gear and the roller, two electro-dynamic machines of like characteristic, a coupling between another of the elements of the gear and one of the electro-dynamic machines and another coupling between a third element of the gear and the remaining

machine, and a variable resistance for altering the relative speeds of the two electro-dynamic machines for the purpose of transmitting, through the gear, a rotary turning effort to the element coupled to the roller.

5 10. In apparatus for the control of a rotary paper reel and the paper web therefrom which supplies a printing machine, a friction band making contact with the periphery of the reel for restraining the rotation of the reel and tensioning the said web, a roller to which one end of the band is attached, an anchorage at the other end of the band and means for rotating the roller for tautening 15 and slackening the belt and so varying the effort of the band on the reel, the means for rotating the roller comprising an epicyclic gear, a coupling between one element of the gear and the roller, an electro-dynamic machine, a coupling between this electro-dynamic machine and another element of the gear, an electro-magnetic friction brake coupled to a further element of the gear, and a variable resistance for regulating the retarding 20 effort of the said electro-magnetic friction brake for retarding the said further element and causing the electro-dynamic machine to impart, through the gear, a rotary turning effort to the element coupled to the roller.

25 30. In testimony whereof I affix my signature.
HENRY VINCENT JAMES.
